UNITED STATES PATENT OFFICE.

McCLINTOCK YOUNG, OF FREDERICK, MARYLAND, ASSIGNOR TO THE
DIAMOND MATCH COMPANY, OF CONNECTICUT.

MACHINE FOR UNFILLING MATCHES.

SPECIFICATION forming part of Letters Patent No. 415,933, dated November 26, 1889.

Application filed May 29, 1889. Serial No. 312,540. (No model.)

To all whom it may concern:

Be it known that I, MCCLINTOCK YOUNG, a citizen of the United States, residing in the city and county of Frederick, in the State of Maryland, have invented certain new and useful Improvements in Machines for Unfilling Matches, of which the following is a specification.

In another application of even date here-
with, Serial No. 312,541, I have shown a ma-
chine for inserting match splints in parallel
rows between the bars of a holding-frame.

My present invention relates to a machine
for removing match-splints from a holding-
frame by inclosing the frame in a box and
separating the parts of the frame so as to
leave the matches stripped therefrom in the
box. This end I attain by inclosing the frame,
with the matches held therein, in a box slotted
on two sides, so as to permit the side pieces
of the frame to project. These side pieces
are then clamped or grasped between holders
in a frame, the movement of one member of
which separates the parts of the frame, with-
draws them from the box, stripping the
matches therefrom in so doing, and leaving
them in regular order in the box. This opera-
tion is facilitated by making the parts of
the holding-frame detachable in such a man-
ner that one of its side pieces may be readily
removed.

The subject-matter claimed is hereinafter
specifically designated. That part of the ma-
chine nearest the operator I call the "front,"
the opposite side the "back" of the machine.
That end of the machine on the right of the
person facing the front I call the "right end"
of the machine, the opposite the "left end."

The accompanying drawings represent so
much of the apparatus embracing all my im-
provements as is necessary to illustrate the
subject-matter herein claimed. Some of these
parts may, however, be used without the oth-
ers, and in machines differing somewhat in
construction from the one herein shown.

Figure 1 represents a top plan of the un-
filling-machine; Fig. 2, a horizontal section
therethrough on the line 2 2 of Fig. 3, look-
ing downward; Fig. 3, a central vertical trans-
verse section therethrough on the line 3 3 of
Fig. 1; and Fig. 4 a vertical longitudinal cen-

tral section on the line 4 4 of Fig. 1. All
these figures show the holding-frames in-
serted in the clamps, ready for separation.
Figs. 5 to 15, both inclusive, represent vari-
ous forms of construction of my improved
splint-holding frame. Fig. 5 is an elevation
of one form of holding-frame, partly in sec-
tion, on the line 5 5 of Fig. 7; Fig. 6, a verti-
cal transverse section on the line 6 6 of Fig. 60
5; Fig. 7, a horizontal transverse section on
the line 7 7 of Fig. 5, showing the matches
inserted; and Fig. 8 a detail view showing
the side piece detachable; Fig. 9, an elevation
of another form of holding-frame; Fig. 10, an 65
edge view thereof; Fig. 11, a section there-
through on the line 11 11 of Fig. 9 with the
splints inserted; Fig. 12, a view of the frame
with its parts separated. Figs. 8 and 12 are
on a smaller scale than the other figures. 70

The main frame consists, essentially, of
two side pieces A A, connected at top by two
cross-bars a' a'. A slide-cam consisting of a
bar B, having inclines b on its inner face,
slides endwise in guides in the top of the 75
frame with its straight edge in contact with
the fixed rear bar a', the cam-bar being re-
ciprocated by means of a lever B', pivoted
thereto and rocking on a pivot b'. The in-
clines on this longitudinal traversing cam- 80
bar work in contact with corresponding in-
clines c on a bar C, movable laterally in suit-
able guides in the frame. The inner edge
of this bar is straight and preferably faced
with rubber or similar material to facilitate 85
its grasp upon the holder-frame against which
it abuts. The opposite or front side of the
holder-frame is provided with a fixed clamp
D, faced similarly to the one above described.

Within the main frame is a sliding frame 90
consisting, essentially, of side bars E, con-
nected by suitable cross-bars and braces and
movable vertically in guides e on the main
frame. A fixed clamping-bar F, extending
across the slide-frame, abuts against one side 95
of the clamp-frame, while the other is held by
a laterally-sliding clamp-bar G, provided with
inclines g, actuated by inclines h on a longi-
tudinally-sliding bar H, actuated by a lever
H'. The construction and operation of this 100
clamping apparatus are essentially similar to
that of the upper one above described.

The holder-frame O consists, essentially, of end pieces O', detachably connected with side pieces O² by ordinary mortise-and-tenon joint or other suitable connections. The holding-bars O³ are likewise detachably secured to the side pieces in a manner similar to that above described. The construction of these holding-frames is more particularly described in the other application, Serial No. 312,541, hereinbefore mentioned. These holding-frames have matches inserted therein and projecting on opposite sides thereon, as shown in the drawings. They are inserted in a box I, having a central longitudinal slot in its bottom and a corresponding one in its top which is readily adjustable and of a size sufficient to admit the holder-frame, which, when inserted, drops through the slot until stopped by the abutting splints, and the top is fitted on in the same manner. The box is then placed on the slide-frame and the protruding part of the holder-frame clamped therein by the appropriate lever. A treadle K, rocking on a pivot k on the main frame, passes between the roller k' on the slide-frame to the front of the machine, where it can readily be reached by the driver's foot. A counter-balance K' always keeps the slide-frame in its elevated position when released from foot-pressure.

The holder-frame is fastened in the lower clamp when depressed. When released, the upward movement of the slide-frame inserts the part of the holder-frame protruding above the box between the edges of the upper clamp, which is then fastened by its appropriate lever. The operator then depresses the treadle, lowering the slide-frame and drawing the sections of the holder-frame apart, thus leaving the matches unfilled when they fall upon the bottom of the box. This operation is repeated with each holder and obviously can be rapidly and expeditiously performed.

In the holder-frame shown in Figs. 5 to 8 the holder-bars O⁴ are secured at one end in a frame-piece O³, permanently secured to one side piece O², their other ends being mortised to fit a tenon on the other or detachable side piece, the whole being held together by a screw o and nut o', this side piece being removed by simply unscrewing this nut, as shown in Fig. 8.

In Figs. 9 to 12 the holder-bars O⁴ are shown as alternately secured by mortise and tenon to the opposite side pieces, and when detached by their being drawn apart, as shown in Fig. 12, one half of the bars remain attached to one side and the other to the other. The bars are also shown as faced on one side with a rubber or other friction-cushion o⁴ to clamp the splints elastically.

Fig. 11 shows the holder-bars O⁴ as made concavo-convex in cross-section for the purpose of slightly bending the splints as they are inserted, so as to cause them to hold by their own resilience.

Having thus fully described the construction, organization, and operation of my im-

proved machine for unfilling match-splints, what I claim therein as new and of my own invention, is—

1. The combination, substantially as hereinbefore set forth, of the splint-holding frame, its inclosing-box, the longitudinally-slotted bottom thereof, and the longitudinally-slotted cover fitting inside the box and over the splint-holding frame, whereby both sides of the frame are left protruding.

2. The combination, substantially as hereinbefore set forth, of a main frame, fixed cross-bars thereon, a clamping-bar moved laterally relatively thereto, the actuating-inclines on the opposite face thereof, and an endwise-moving slide-cam actuating the clamping-bar to hold or release the upper side of the splint-holding frame.

3. The combination, substantially as hereinbefore set forth, of a main frame, a clamp fixed therein, a corresponding clamping-frame reciprocating in guides, locking-clamps, and actuating-cams, whereby each side of the splint-holding frame is grasped by its respective clamp to separate it.

4. The combination, substantially as hereinbefore set forth, of a fixed clamp, a reciprocating clamp, a counterpoise connected therewith, and a treadle or actuating-lever, whereby the clamps when released automatically resume their proper position for grasping the splint-holding frame.

5. A splint-holding frame consisting of the combination of parallel holding bars or clamps, and a detachable side piece to facilitate the stripping of the splints from the holder by moving them sidewise.

6. The combination, in a splint-holding frame, of side pieces having mortises therein, holding-bars, and tenons thereon alternately secured to opposite side pieces, substantially as set forth, so that when separated the alternate bars remain attached to their respective side pieces.

7. The combination, substantially as hereinbefore set forth, in a splint-holding frame, of parallel bars with side pieces to which they are alternately secured, so that when separated the one set of bars remain with one of the side pieces and the other set with the opposite side piece.

8. A splint-holding frame consisting of a series of holding-bars concavo-convex in cross-section to retain the splints therein by their own resilience.

9. A splint-holding frame consisting of a series of concavo-convex splint-holding bars faced with elastic material to hold the splints by their own resilience, combined with that of the elastic material.

In testimony whereof I have hereunto subscribed my name.

McCLINTOCK YOUNG.
